UNITED STATES PATENT OFFICE.

WILLIAM H. BAKER, OF BRIDGEPORT, CONNECTICUT, ASSIGNOR OF ONE-HALF TO JOSEPH P. FRISBIE, OF BRIDGEPORT, CONNECTICUT.

MEAT-TENDERER.

No. 866,106.

Specification of Letters Patent. Patented Sept. 17, 1907.

Application filed March 21, 1907. Serial No. 363,573.

To all whom it may concern:

Be it known that I, WILLIAM H. BAKER, a citizen of the United States, residing at Bridgeport, county of Fairfield, State of Connecticut, have invented a new 5 and useful Meat-Tenderer, of which the following is a specification.

This invention has for its object to provide a meat tenderer which shall be strong, durable and equal in efficiency to any of the same class now upon the market 10 and which shall be so simple and inexpensive to produce as to permit of its being retailed for ten cents with a fair profit both to the manufacturer and dealer.

With this end in view I have devised a meat tenderer consisting only of cutter strips, two end plates 15 and a wire handle.

In the accompanying drawing forming a part of this specification, Figure 1 is an elevation of my novel tenderer; Fig. 2 an end view; Fig. 3 a section on the line 3—3 in Fig. 1; Fig. 4 an elevation of one of the end 20 disks detached; and Fig. 5 is an elevation of one of the cutter plates, detached. Fig. 6 represents a detail section on line 6—6 of Fig. 2.

10 denotes the cutter head and 11 the handle. The cutter head consists simply of a plurality of cutter strips, indicated by 12, and two end plates, indicated by 13. Each cutter strip comprises a series of cutting teeth, indicated by 14, and an attaching lug 15 at each end of the strip. The end plates are provided with central holes, indicated by 16, and with radial slots, 25 indicated by 17, which receive the attaching lugs. In assembling, the cutter strips are placed radially 30 between the end plates. The attaching lugs are made

slightly longer than the thickness of the end plates and engage the radial slots closely, the ends of the cutter strips abutting against the end plates. The 35 ends of the attaching lugs are then headed down (see Fig. 6) locking the cutter strips to the end plates and forming a strong and rigid cutter head which will stand the strain of use for practically an unlimited length of time. 40

The handle consists of a piece of relatively heavy wire bent at its mid-length to form arms 18 which are shown as converging, although this is immaterial. Contiguous to the handle portion, the arms are bent outward to form a yoke 19 which receives and half 45 incloses the cutter head. The ends of the arms are inwardly turned forming hubs 20 which are sprung into the holes 16 in the end plates, the yoke preventing lateral movement of the cutter head but without close engagement therewith, so that the cutter head is left 50 free to rotate on the hubs.

Having thus described my invention I claim:

A meat tenderer consisting of a cutter head comprising a plurality of cutter strips each having a series of cutting teeth and attaching lugs at the ends, and end plates each 55 having a central hole and a plurality of radial slots to receive the attaching lugs, said lugs being headed down to lock the cutter strips and end plates together, and a handle engaging the holes in the end plates.

In testimony whereof I affix my signature, in presence of 60 two witnesses.

WILLIAM H. BAKER.
